UNITED STATES PATENT OFFICE.

MILTON H. SHOENBERG, OF SAN FRANCISCO, CALIFORNIA, ASSIGNOR TO MAJESTIC ELECTRIC DEVELOPMENT COMPANY, OF SAN FRANCISCO, CALIFORNIA, A CORPORATION OF CALIFORNIA.

ELECTRIC IRON.

Application filed March 4, 1922. Serial No. 541,156.

To all whom it may concern:

Be it known that I, MILTON H. SHOENBERG, a citizen of the United States, and resident of the city and county of San Francisco, State of California, have invented new and useful Improvements in Electric Irons, of which the following is a specification.

My invention has for its object an electric iron whose several parts are constructed and arranged to increase the efficiency of ironing therewith; to reduce the muscular strain on the operator; to increase the heat equalizing and heat retaining qualities over irons heretofore constructed; to simplify the construction and increase the reliability.

Other objects will appear from the drawings and specifications which follow:

Figure 1 is a side view of my iron.

Fig. 2 is a plan view of Fig. 1.

Fig. 3 is a cross section through the rear portion of the iron, showing the electrical connections and their manner of support and attachment to the iron frame and is taken on the line III—III of Fig. 2.

Fig. 4 is a section of the electric terminals and sheath parts of Fig. 3 taken on the line IV—IV thereof.

Fig. 5 shows a portion of the iron frame bent and drilled ready to receive the electrical connections and is a section of the iron frame on the line V—V of Fig. 4 and of the frame of Fig. 3 with certain of the parts removed.

Fig. 6 is a side view of my iron on a reduced scale to show the angle of the handle and the manner in which this angular mounting contributes to a reduction of muscular strain for the operator.

Fig. 7 is a diagrammatic showing of the winding of the heating element to secure the most efficient distribution of heat.

Fig. 8 is a reduced scale plan drawing of the base of my iron having superimposed thereon a dotted line showing of the conventional iron shape as heretofore constructed.

Fig. 9 is an enlarged fragmentary cross section on the line IX—IX of Fig. 8 of the outline of the conventional iron shown dotted in and a full line showing of a cross section of my iron to better illustrate the manner in which the metal is distributed to secure a perfect heat distribution and better heat radiation.

Throughout the figures similar numerals refer to identical parts.

Referring particularly to Fig. 1 the iron consists of a base 1 and casing 2 and handle support 3, handle 4, sheath 5 and heating element shown dotted in at 6, 7, and 8, and electrical connections at 9 having terminals 10 within the sheath. In Figure 7, where the winding of the heating element is shown diagrammatically, the insulated foundation 30 is of mica or other suitable insulation on which the windings 6, 7, 8, are disposed unequally in order to concentrate the heat where most desired, as will be explained below.

Electric terminal connections at 10—10 are best shown in Figs. 3, 4, where the frame 2 is punched and bent as shown at 12 Fig. 5. Insulations 13, 14, 15, are then assembled about the hole 16 in the leaf 12 of the frame 2 and the connections 10—10 are thus insulated therethrough and fastened by conventional nuts. One of the terminals 9 is connected to each of these connecting posts 10—10. The sheath 5 is secured to the handle support 3 and spaced from the base frame 2, thereby preventing the transfer of excessive heat from said frame and base.

At 18 Figs. 8 and 9 is shown by dotted lines the outline of the conventional iron base as distinguished from the shape I have adopted. By making the base 1 thicker and by taking some of the metal from the sides and corners of the conventional form of iron and building into the center of the base, see Figs. 8 and 9, I secure a larger reservoir of heat which is readily distributed to or from the toe 21 and heel 22 of the iron and secures at all times a perfect equalization and a high degree of heat retention, and this heat reservoir thus prevents scorching the work on the one hand or chilling the work on the other.

By reducing the width of this conventional base without changing the length or weight of my iron I have better distributed the metal securing a thicker base, the increased thickness attained being shown by the dimension line 20, Fig. 9. In this way the heat is better retained and the iron more quickly and efficiently heated.

Particular attention is directed to the angle at which the handle 4 is mounted, see Fig. 6. A line normal to said handle is

shown at 24 which is parallel with the average position of the forearm of the operator during the movement of the iron. The swinging of the said forearm being indicated by the extreme positions 25, 26 as the iron is moved back and forth. This handle position reduces the muscular effort of the entire arm of the operator and particularly reducing wrist and finger strain, and results in more efficient operation.

As the iron is moved in the direction of the arrow 27 across the material being ironed the front of the iron is called upon to give up the greatest amount of heat and it will be seen from the winding indicated in Fig. 7 that the resistance wire is concentrated at 6 whereby a large amount of heat supply to the toe or front of the iron is secured. When the iron movement is reversed as shown by the arrow 28, Fig. 6, the heel of the iron 22 is called upon to give the greatest amount of heat and this is provided for by the distribution of the winding of the resistance wire at 8.

25 I claim:

1. In an electric iron a heating unit comprising an electrical resistance wound on insulation material of substantially flat wedge shape, said windings being spaced close together on the narrow part of the wedge, further apart over the wide part of the wedge.

2. In an electric iron a heating unit comprising an electrical resistance wound on insulation material of substantially flat wedge shape, said windings being spaced close together on the narrow part of the wedge, further apart over the wide part of the wedge, and a space between said parts across which said windings are electrically connected.

40 3. In an electric iron a heating unit comprising an electrical resistance wound on insulation material of substantially flat wedge

shape, said windings being spaced close together on the narrow part of the wedge, further apart over the wide part of the wedge, 45 and a space between said parts across which said windings are electrically connected, and a metallic base member adjacent said unit and having a smooth surface on the opposite side, said base formed as a circle on its heel 50 and straight line sides converging to a sharp point as and for the purpose set forth.

4. An electric iron comprising parts as set forth in claim 3 and a casing which with said base encloses said unit, said casing having a leaf formed integral therewith and extending upward at an angle and providing an opening through said case and a support for electrical terminals.

5. An electric iron comprising parts as set forth in claim 3 and a casing which with said base encloses said unit, said casing having a leaf formed integral therewith and extending upward at an angle and providing an opening through said case and a support 65 for electrical terminals, and electrical terminals connected through said opening to said unit.

6. An electric iron comprising parts as set forth in claim 3 and a casing which with 70 said base encloses said unit, said casing having a leaf formed integral therewith and extending upward at an angle and providing an opening through said case and a support for electrical terminals, and electrical terminals connected through said opening to said unit, and a sheath spaced from said casing and surrounding said terminals.

7. An electric iron having a handle spaced above said iron and sloping upward from 75 the heel toward the toe of said iron in combination with parts as set forth in claim 6.

MILTON H. SHOENBERG.
